UNITED STATES PATENT OFFICE.

JAMES E. YORK, OF NEW YORK, N. Y., ASSIGNOR TO YORK ROLLING PROCESS COMPANY,
A CORPORATION OF NEW YORK.

PROCESS OF MAKING SHAPES FOR COLUMNS AND THE LIKE.

1,037,099.

Specification of Letters Patent. Patented Aug. 27, 1912.

Application filed June 30, 1905. Serial No. 267,833.

To all whom it may concern:

Be it known that I, JAMES E. YORK, a citizen of the United States, residing in the borough of Brooklyn, county of Kings, city 5 and State of New York, have invented certain new and useful Improvements in the Process of Making Shapes for Columns and the Like, of which the following is a specification.

10 This invention aims to provide a simple and convenient method of forming steel shapes for columns and the like, which process lends itself readily to the formation of shapes now in use, and by which also certain shapes may be made which have been 15 hitherto impossible.

The special advantage of the process is in the facility with which the desired shapes may be rolled from old rails, beams or the 20 like.

Other advantages are referred to in detail hereinafter.

The accompanying drawings illustrate embodiments of the invention.

25 Figures 1, 2, 3 and 4 illustrate the successive steps of transforming a part of an old rail into a substantially semi-circular flanged shape by a combined rolling and stamping operation; Figs. 5 and 6 illustrate 30 the method of forming another shape by a combined rolling and bending operation; Figs. 7 to 15 inclusive illustrate various shapes which may be rolled by the new process. Figs. 16 and 17 are elevations of the 35 columns showing the particular constructions.

An important feature of the invention is in the rolling of the flange or head of a rail, or of any other elongated flanged shape laterally, so as to spread such flange into a wide 40 thin plate, with a stiffening flange (originally the web) at an intermediate point. In making more complicated shapes it is proposed in addition to press or stamp or otherwise 45 bend the central portion or the edge of such a plate to bring it to the desired shape, and to form the flanges thereon for stiffening the edge, or fastening it to an adjacent section. In connection with the rolling or the stamping 50 operation, the plate may be embossed by

suitably shaping the die so as to give it any ornamental or useful configuration desired.

Referring now to the drawings, the old rail shown in Fig. 1 and composed of a web A, a base or flange B, a head C which is in effect a thick flange worn to a rather irregular top face, may be divided, preferably by a rolling operation, into the member shown in Fig. 2 comprising a head C intact, and a flange D originally constituting a part of the web of the rail. The shape shown in Fig. 2 may then be transferred to a machine such as is illustrated in my applications Numbers 177,989 and 236,354 filed respectively October 21, 1903 and December 10, 1904, and laterally rolled to spread the head C into a wide thin plate E. The spreading is accomplished by laying the member on a bed F of suitable configuration, and rolling laterally over the member a pressure roller 60 G back and forth a sufficient number of times to secure the desired spreading, the portion of rail being first heated to the desired extent. The plate E with the flange D may thereafter be transferred to a bending or stamping machine comprising a lower die H and an upper die J of suitable configuration, and by bringing down the die J, the plate is pressed into a substantially semi-circular portion K with flanges L at the 65 edges. The lower die may also be shaped to form bosses M or other ornamental or useful projections on the faces of the member.

70 Thus by a very simple series of operations it is possible to secure a plate of any desired width and shape in cross-section, with an integral flange at the center and at each edge, this being a shape which is very useful, and also very difficult or impossible to obtain by the usual rolling processes. In addition, 75 the extra rolling of the metal increases its quality, especially the lateral rolling of one portion, while another portion, the flange D, has been rolled longitudinally.

By slight variations of the operations described a great number of final shapes may be obtained, some of which are difficult and others impossible to obtain in any other way. For example it would be impossible 80 to longitudinally roll wide thin flanges such 85

as constitute the plate E or the plate N hereinafter referred to. Such wide flanges could only be rolled by giving them an extreme taper which, the quantity of metal being limited, soon limits the width of the flange. For example the rail of Fig. 1 need not be divided, but may be subjected to a lateral rolling of both the head and the base so as to form two wide thin plates N (Fig. 10 5) connected by the web A, after which the plates N may be bent at the edges in any suitable way to form flanges O, thus producing an ideal section for columns made of a single piece, and having a very excellent 15 distribution of the material to resist column strains. In fact in a single integral member there are obtained all the advantages of proper distribution of the metal and convenience of making joints, which have made a 20 similar built-up section perhaps the most popular among engineers. This built-up section is formed ordinarily of four Z-bars riveted to a central plate. This figure illustrates in a most striking way the advantages 25 of the present process.

Fig. 7 illustrates a section of the complete column made up of two of the members indicated at Fig. 4, with the flanges L riveted to each other, thus providing a section similar 30 to the well-known Phenix section consisting of a ring with radial flanges. The ordinary Phenix section is made up of four or six separate arcs, while according to the present invention it may be made up of only 35 two such arcs.

Fig. 8 illustrates a slight modification of the shape of Fig. 7, the plates K being angular instead of circular so as to form an octagonal column.

Fig. 9 illustrates a column section built up of members of two different styles. In one style the web A is intact and the plate N is formed from the head or the base, while the thicker plate N' at the opposite side is 45 formed from the base or the head as the case may be. In the other style the plate N' is formed of either the head or base of the rail, and a thin flange A' is formed by rolling out the web of the rail, or by the use of a 50 deeper rail or I-beam or the like.

Fig. 10 indicates a shape similar to that of Fig. 7, but in which the plate K is of such shape as to constitute a square column instead of a circular one. It is understood 55 that the embossing indicated at M in Fig. 7 may be added or not at will.

Fig. 11 indicates a variation of the shape of Fig. 10 in which the flange D extends into the interior of the column instead of 60 outward, thus economizing space without losing very much in the strength of the section.

Fig. 12 is a variation of Fig. 7 in which the complete column will be hexagonal instead of circular.

Fig. 13 is a variation of Fig. 7 in which the flange D is on the inside to economize space.

Fig. 14 illustrates a very excellent section which may be made of two identical members having central wide flanges A, and plates N with flanges O' bent downward, that is to say, at the same side of the web A; the two members being riveted to each other back to back.

Fig. 15 illustrates a direct variation of Fig. 6 in which the flanges O instead of being bent outward are bent inward toward each other, the proportions of the parts being such as to maintain a substantially square plane.

The operation of spreading the flanges to form the plates N in Fig. 5 may be stopped at any suitable point so as to obtain an I-beam, or more accurately an H-beam with very wide thin flanges of uniform thickness throughout their width, such as could not possibly be rolled by any other process. Such a shape would be extremely useful either as an integral simple column section, or as a beam.

By suitably ribbing or grooving the roll and bed or the dies of Figs. 3 and 4, sockets P (Fig. 16) may be formed at one end of each section manufactured, adapted to fit over the opposite end of the column to make a good joint. Also by a suitable modification of the roll and support or of the dies, the flanges may be provided with interlocking projections Q and recesses R (Fig. 17).

The product described is not separately claimed in the present application, but I am not to be understood as thereby waiving my right to claim the same in a separate application.

Though I have described with great particularity of detail certain specific embodiments of the invention, yet it is not to be understood therefrom that the invention is limited to the particular embodiments disclosed, various modifications of the process, and of the several products, may be made by those skilled in the art, without departure from the invention.

What I claim is:

1. The process of forming a column section having a longitudinal rib and longitudinal flanges which consists in taking a rail head with part of the web thereon and spreading, flanging and concaving the metal of said head.
2. The process of forming a column section having a longitudinal rib and longitudinal flanges which consists in taking an

elongated shape having a head and a rib and spreading, flanging and concaving the metal of said head.

3. The process of forming an elongated structural shape having a longitudinal projection intermediate of its edges and having longitudinal flanges along its edges, which consists in taking an elongated shape having a head and a longitudinal projection and

spreading the metal of said head and bending flanges on the edges thereof. 10

In witness whereof, I have hereunto signed my name in the presence of two subscribing witnesses.

JAMES E. YORK.
